CREELS

John Kreuthmeier, St. Paul, Minn.

Application July 24, 1958, Serial No. 750,702

7 Claims. (Cl. 206—51)

This invention relates to an improvement in creels and deals particularly with a means of supporting heavy fabrics such as those made to simulate fur, velvet and the like.

For many years heavy fabrics have been supported on devices known as creels during shipment of the goods from the manufacturer to the consumer. These creels normally comprise end frames having a center portion and two pairs of outwardly diverging arms extending in opposite directions from said center portions. These frames are held in properly spaced relation by a spacing member which is of a length substantially equal to the width of cloth being shipped. Each of the four outwardly diverging arms on each of the end frame members is provided with an equal number of inwardly directed hooks. These hooks on opposite ends of the frame engage into the marginal edge of the fabric strip to support the fabric between the pairs of hooks. The fabric is normally attached by hooking the side edges of the end of the strip upon two innermost hooks of one of the arms, next hooking the edges of the strip on the innermost hooks of the next adjoining arm, hooking the edges of the strip between the hooks of the next adjoining arms, hooking the edge of the strip between the innermost hooks of the fourth arm and continuing this operation by then hooking the edges of the strip between the second innermost hooks of the first arm and continuing this process until the fabric is all looped between the various arms, the loops of fabric gradually increasing in size until the outermost hooks are reached. As the creels are relatively expensive to produce, the end frames are usually removed from the intermediate spacing member and laid flat against the intermediate spacing member and are normally returned to the manufacturer in this disassembled form for reuse.

While creels of this type have been used for a great number of years, very considerable time and effort is expended both in attaching the strip of fabric to the creel at the point of manufacture, and also in detaching the fabric from the creel for use. In detaching the fabric, the strip is disconnected in a reversal of the manner in which it is connected, starting at the outer end of the strip and disconnecting each pair of hooks while rotating the creel until it is disconnected. Due to the time which is required in disconnecting the fabric, there is a material tendency to pull the edges of the fabric from the hooks tearing the edges of the fabric and causing considerable damage to it. While the edges of the fabric are usually trimmed off in many instances, the tearing of the edges still has a tendency to injure the inner portions of the fabric and the tears make the edges more difficult to trim. It is an object of the present invention to provide a creel which is generally similar to those previously in use but which provides a means of greatly simplifying the detachment of the fabric from the creel when it arrives at its destination, thus very materially decreasing the time and effort normally expended for this work.

2

A feature of the present invention resides in the provision of a creel which may be of the same general type of creels in common use but in which the hooks are mounted upon plates hingedly connected to the arms of the creel. The hook supporting plates are so arranged that the tension of the fabric between the hooks tends to hold the plates in alignment with the various hooks engaged in the edges of the fabric. However, by manually pivoting these plates, a series of hooks may be simultaneously disengaged with the fabric, permitting the fabric to be removed by merely unwinding it from the reel.

In creels of usual type, the hooks are normally arranged flat and in a common plane with the pointed ends of the hook being directed toward the outer ends of the arms. In the present arrangement, the ends of the hooks are bent at right angles or formed at right angles so that the planes of the hooks are parallel. This does not in any way effect the operability of the hooks, but permits the hooks to be simultaneously disengaged by a simple pivotal movement of the hook supporting plates.

These and other objects and novel features of the present invention will be more clearly and fully set forth in the following specification and claims.

In the drawings forming a part of the specification: Figure 1 is a perspective view of the creel in readiness for use.

Figure 2 is a diagrammatic view of an end of the creel showing the manner in which the fabric is supported in substantially concentric loops about the longitudinal center of the creel.

Figure 3 is a perspective view of a series of hooks showing the manner in which they are mounted and hingedly supported.

Figure 4 is a sectional view through a portion of one of the arms of the creel showing the hooks in fabric engaging position.

Figure 5 is a view similar to Figure 4 showing the hooks in disengaging position.

The creel is indicated in general by the letter A. The general shape of the device is similar to that of other creels and it includes a pair of opposed end frames 10 and 11 which are identical in form but reversed in relation to each other. Each end frame includes an elongated metal strip bent to form the general outline of an hour glass. The strip includes a pair of parallel center portions 12 and 13 having outwardly diverging frame portions 14 and 15 connected to the upper ends thereof. These outwardly and upwardly diverging frame portions are connected by a horizontal top connecting member 16. The lower ends of the intermediate portions 12 and 13 are connected to outwardly and downwardly diverging frame portions 17 and 19 respectively which are connected by a cross connecting member 20. In view of the fact that the frames 10 and 11 are similar, the various portions thereof have been given similar identification numerals.

The end frames 10 and 11 are held in properly spaced relation by a central spacing member indicated in general by the numeral 21. The spacing member 21 includes a pair of parallel spacing bars 22 and 23 which are held in parallel relation by cross braces 24 and 25. The ends of the parallel bars 22 and 23 are secured between the parallel end frame members 12 and 13 by bolts 26 or other suitable means. These bolts 26 may be removed so that the end frame members may be placed upon the spacing members 21 for return to the manufacturer.

The hooks which are usually connected to the various diverging arms of the end frame members are normally stamped from a flat strip of sheet material so that the hooks are in a single plane. The present structure dif-

fers from the conventional structure in that the hooks are arranged in parallel planes at right angles to the plane of the base of the strip from which they are punched. As indicated in Figure 3 of the drawings, a flat strip of sheet material 27 is punched to provide a series of hook shaped projections 29 and these hooks are twisted so that the hook ends thereof are in substantially parallel planes at right angles to the plane of the base portion of the strip 27.

As indicated in Figures 4 and 5 of the drawings, each strip 27 is riveted or otherwise secured as indicated at 30 to an elongated hinge plate 31 which is hingedly connected at 32 to a second cooperable hinge plate 33. The hinge plate 33 is riveted or otherwise secured as indicated at 34 to one of the diverging arms 14, 15, 17 or 19. The hinges are attached to the diverging arms in such a manner that the hook ends extend inwardly toward the opposite frame ends. Thus, when the hinge plates are folded into the normal position illustrated in Figure 4 of the drawings, the fabric B may be readily hooked over the inwardly directed hooks.

In preferred form of construction, two assemblies of the type illustrated in Figure 3 of the drawings, are secured in end abutting relation to each of the diverging arms mentioned. Obviously, this may be varied, and if preferred three such assemblies or a greater number may be employed, or all of the hooks may be mounted upon a single hinge plate in the event all of the fabric is to be always be removed at one time.

It will be noted from the drawings, that a rearward projection 35 may be provided on each hinge plate extending the full width of the strap iron or similar metal forming the end frames of the creel. An angularly turned flange 36 is provided on the projection 35 which may engage over the outer edge of the frame strip with some resilience or tension if desired. The flange 36 provides a means of grasping the hinge plates to pivot the same to remove the fabric.

In use, the creel is set up in the form illustrated in Figure 1 and the end of the strip is hooked between the innermost hooks of two parallel diverging arms at opposite ends of the unit. In other words, the fabric may be hooked between the innermost hooks of the arm 15 of the frame 10 and the arm 14 of the frame 11. The fabric may then extend downwardly and hook over the innermost hooks on the arm 19 of the frame 10 and the arm 17 of the frame 11. The fabric may then extend between the innermost hooks on the arm 17 of the frame 10 and the arm 19 of the frame 11. The fabric will then be connected between the innermost hooks of the arm 14 of the frame 10 and the arm 15 of the frame 11. From this point, the fabric may be hooked between the second innermost hooks of the arm 15 of the frame 10 and the arm 14 of the frame 11 and subsequently between the next innermost hooks of each of the arms and so forth until the fabric is completely looped within the frame as indicated in Figure 2 of the drawings.

When the fabric reaches its destination, either one-half or the entire length of strip may be quickly removed from the creel by swinging the hinged plate 31 from the position shown in Figure 4 of the drawings to the position shown in Figure 5 thereof. During this pivotal movement, the points of the hooks 29 are simultaneously disengaged from the fabric strip. By pivoting the outermost four hook units on each frame end, one-half of the fabric will be disengaged from the hooks and may be merely unrolled from the creel. If it is desired to remove all of the fabric, all of the hooks may

be disengaged by pivoting the innermost four hook units from the position shown in Figure 4 to the position shown in Figure 5, releasing the remainder of the fabric.

It will be seen that through the use of my creel, the fabric may be removed from the creel in a small fraction of the time normally required for this work and with no subsequent damage to the fabric. The hooks are preferably arranged so as not to exert an excessive pull upon the fabric during the pivotal movement of the hooks as is evidenced from an examination of Figures 4 and 5 of the drawings.

In accordance with the patent statutes, I have described the principles of construction and operation of my improvement in creels, and while I have endeavored to set forth the best embodiment thereof, I desire to have it understood that changes may be made within the scope of the following claims without departing from the spirit of my invention.

I claim:

1. A creel including an elongated central spacing member and a pair of parallel end frames secured thereto, each end frame including a series of diverging arms between which the fabric may be supported, a hinge plate hingedly connected to each of the arms, and a series of spaced hooks fixedly attached to each hinge plate, the spaced planes of the hooks being substantially parallel and being at substantially right angles to the axis of pivot.

2. The structure of claim 1 and in which each of the arms includes a plurality of hook bearing hinge plates in longitudinal alignment.

3. A creel including a central spacing member, end frames connected to opposite ends of said spacing member, each end frame including an intermediate portion connected to said spacing member, a pair of upwardly and outwardly diverging arms, and a pair of downwardly and outwardly diverging arms, a hook unit hingedly connected to each of said arms, the axis of pivot being parallel to the axis of the arms, each hinge unit including an elongated hinge plate and a series of parallel hooks fixedly connected to said plate, and residing in spaced planes extending at right angles to said pivot axis, the ends of the hooks being adjacent the pivot point of the hinge plate.

4. The construction described in claim 3 and in which each of said diverging arms supports a plurality of hook units in longitudinal alignment.

5. The construction described in claim 3 and in which each of the hook units is attached to the outer surface of a diverging arm.

6. The construction described in claim 3 and including means on each hinge plate which may be engaged by the fingers for pivoting the hinge plate.

7. The construction described in claim 3 and in which the pointed ends of the hooks are directed away from the opposite end unit in one pivotal position of the hinge plate and inclined slightly toward the opposite end frame in another position of the hinge plate.
